No. 826,231.

PATENTED JULY 17, 1906.

C. DEL CAMPO.

ELECTRIC APPARATUS FOR PREVENTING TRAIN WRECKS.

APPLICATION FILED NOV. 15, 1905.

UNITED STATES PATENT OFFICE.

CARMELO DEL CAMPO, OF NEW YORK, N. Y.

ELECTRIC APPARATUS FOR PREVENTING TRAIN WRECKS.

No. 826,231.

Specification of Letters Patent.

Patented July 17, 1906.

Application filed November 15, 1905. Serial No. 287,534.

To all whom it may concern:

Be it known that I, CARMELO DEL CAMPO, a citizen of Italy, residing in New York, in the county of New York and State of New York, have invented a new Electrical Railway Safety Appliance, to be known as "Electric Apparatus for Preventing Train Wrecks," by which train wrecks will be avoided, of which the following is a specification.

10 The apparatus is illustrated in the accompanying drawings, in which Figure 1 is a side view of the entire apparatus.

A B is a wooden board on which the apparatus is mounted. Said board is pierced by 15 a hole on each of the four corners and screws on the side of the tender of the locomotive. The iron lever *a* revolves on stud *b*, which permits it to oscillate in either direction. The upper end *c* of said lever has a shape of a 20 disk, and the lower end has a slot on which is attached a piece of leather *d*, held fast by two screws.

25 The sector *e*, fastened to the board by screws and nuts at *ff*, acts as a guide to the lever when the same changes its perpendicular position. The lever follows the curve of the said sector, sliding beneath the same.

Fastened beneath the lever below the sector there is a curved spring *g*, which having 30 the shape of an arch the two ends slide on the board. This is to keep the lever raised up against the sector.

At the right of the upper end of the lever there is a screw with large head *h*, on which, 35 almost touching it, there is a flat spring *i*. The clearance between the screw *h* and the spring *i* is about the thickness of Bristol card-board. At the lower right-hand side there is an electric battery *j*, fastened on the board 40 by metal strap *k*, and on the top there is an electric bell *l*.

The wiring is done as follows: The wiring starting from the carbon goes to the bell, the other wire from zinc goes under the flat 45 spring *i*, being in contact with the same, and the third wire from button *h* to the bell again, and by pressing down spring *i* this coming in contact with button *h* will close the circuit, and the bell will ring.

50 It is to be understood that the wires run in grooves on the back face of the board, which being covered by magnet-covering cloth will make wires invisible. At the left-hand side of the upper end of the lever there is a cylinder *m*, containing a piston which is kept

pushed by a spiral spring and controlled by a nut on the back. This is to push back the lever on its perpendicular position in case it should be shifted from left to right. At a distance of one-tenth of its length from the 60 upper end of the sector there is a flat spring *n*, put upon a piece of metal of the same thickness of the lever, as shown by dotted lines. This is to hold the lever on that point when wanted. The handle *o* is for shifting 65 the lever to point *n*.

Fig. 2 shows a cast-iron column *1*, having on its top a piece of leather *3*, held fast by two screws same as the lower end of the lever, Fig. 1. Said column is situated on the opening-switches of railroad-tracks.

Let us place my apparatus at the right-hand side of the tender of a locomotive and allow the same to run on tracks which at a certain point has a switch that leads to a 75 dead track on which cars are stationed. The locomotive running on first track, finding the switch left open by carelessness on the part of an employee, will certainly go ahead and wreck the cars standing on the siding. Let 80 us now have this locomotive supplied with my apparatus, and we will find that as soon as the locomotive enters the switch the lower end *d* of the lever will be pushed back toward the left by the top end *3* of the column. This 85 pushing will cause the lever to go in a position shown by dotted lines, Fig. 1, and the top end of the lever, pressing down spring *i* on button *h*, will cause the bell to ring, calling the attention of the engineer that he is running on a wrong track. Backing up the engine, the two leather ends *d*, Fig. 1, and 3, Fig. 2, will come in contact again, and the lever will be pushed back to its previous perpendicular position, causing thus the bell to 95 stop ringing and the lever ready for another similar case.

In case the engine supplied with my apparatus has to go backward and forward frequently to avoid the bell from ringing often 100 the engineer by means of handle *o* pulls the lever as far up as it can go, which will be at the point *n* when caught by the spring, as shown by the dotted lines, Fig. 1.

When the engineer is through maneuvering, he will push the lever in its proper place.

Having thus fully described my invention, I claim—

In an electric railway signaling device with a bell, located in an electric circuit 110

which is closed and broken by means of a spring and a button, a vertical lever oscillating on a stud, said lever provided with a piece of leather attached at the lower end, a chambered plunger located near the upper end of the lever and controlled by a spiral spring which keeps the lever on its vertical position, a handle attached to the lever to pull same

by hand when action of apparatus is not wanted, a sector acting as guide to the circular motion of lever.

CARMELO DEL CAMPO.
